SHEET GRIPPER

Christen R. Kaddeleand, Shelton, Conn., assignor
to Harris-Seybold-Potter Company, Cleveland,
Ohio, a corporation of Delaware

Original application September 4, 1941, Serial No.
409,547. Divided and this application March
12, 1942, Serial No. 434,401

12 Claims. (Cl. 101—409)

This invention relates to improvements in sheet grippers, that is to say in mechanism for gripping sheets of paper, at their forward edges, and conveying them from a feeding means to an operating means, from one operating means to another, from an operating means to a delivery means, etc. The present invention finds its principal utility, however, in connection with endless conveyors for sheets, and is a division of my co-pending application, Serial No. 409,547 filed September 4, 1941.

One of the objects of the invention is the provision of sheet grippers particularly adapted for use upon endless conveyors.

Another object is the provision of gripper units with self-contained springs, the units being adjustable along the gripper shaft, and eliminating the necessity for separate spring means to urge the shaft toward sheet gripping position.

Still another object is the provision of a spring arrangement such that the leverage through which the spring acts shall be greatest in the position in which the grippers are closed, at which time the spring is expanded and hence unable to exert as much force as when the grippers are open.

Other objects and features of novelty will appear as I proceed with the description of that embodiment of the invention which, for the purposes of the present application, I have illustrated in the accompanying drawings, in which:

Fig. 1 is a fragmental plan view of an endless conveyor comprising a gripper bar equipped with my improved sheet grippers.

Fig. 2 is a cross-sectional view of the gripper bar in operative relation with a drum at one end of an endless conveyor.

Fig. 3 is a detail plan view on a larger scale showing one gripper unit and one stop unit for limiting the rotation of the gripper shaft toward sheet gripping position.

Fig. 4 is a detail sectional view on a larger scale taken substantially on the line 4—4 of Fig. 1.

Figs. 5 and 6 are further transverse detail sectional views taken substantially on the lines 5—5 and 6—6 of Fig. 1.

Fig. 7 is an elevational view of one end of my gripper bar with one of the supporting chains therefor running between a pair of superposed tracks, and

Figs. 8 and 9 are diagrammatic views illustrating the difference in leverage exerted by a unit spring in the gripping and ungripping positions, respectively.

While the present invention may be employed

in connection with drums or cylinders in various sheet handling machines, it is illustrated herein as applied to an endless conveyor embodying a pair of endless chains 10 running over pairs of sprockets, not shown, and supported and guided between sprockets in tracks each of which comprises an upper member 11 and a lower member 12.

The conveyor comprises in addition to the chains 10 a plurality of transverse bars 13 mounted at their ends in the chains, each of these bars with its associated parts being adapted to grip the forward edge of a sheet and transport it from the taking position to a position at which it is transferred to another operating mechanism or to a sheet delivering mechanism.

The chains 10 comprise the usual side links 14 and pins 15, but contrary to usual practice, each pin 15 carries three independently rotatable rollers 16, the outer rollers bearing on runways 8 of track member 12 and the inner roller bearing upon a runway 9 of track member 11. The arrangement of runways is such that each roller tends to rotate in one direction only as it travels from one drum to the next, and looseness between the tracks and chain is eliminated. At the points of the conveyor where bars 13 are secured to chains 10, three of the pins 15 are made longer than the rest and carry flanged sleeves 17 held in place by cotter pins 18. Each of the groups of three sleeves supports an end plate 19, one for each end of the bar, in the manner best shown in Fig. 7, and plate 19 is provided with two parallel slots extending in the general direction of the pitch line of the chain and one slot midway between the other slots and at right angles thereto. The sleeves 17 have flat sides which fit slidably into these slots, as illustrated more in detail in my copending application previously referred to. By means of the construction described, the position of each end plate transversely of the pitch line of the chain is determined by the outermost sleeves 17 and its position longitudinally of the pitch line by the intermediate sleeve. At the same time the sleeves are free to slide in their slots to accommodate themselves to the various degrees of curvature of the chain path.

Each of the end plates 19 is formed with a lateral extension 20 which is provided with a beveled end surface 21 and beveled side portions 22 and 23 for purposes of accurate registration with the drums over which the conveyor passes. Extensions 20 are secured by screws 24 to the end portions of gripper support bar 13 which extends across the conveyor from one extension 20 to

the other. Centrally of the bar 13 a plate 25 is secured by screws 26, this plate being provided with beveled portions similar to bevels 22, 23 of plate extensions 20. Gripper bar 13 is provided with integral bearing portions 27 and 28 in which is journaled gripper shaft 29. Mounted upon this shaft at proper intervals are a plurality of grippers each of which comprises a dog 30 fixed to shaft 29 by a screw 31, a gripper finger 32 loose on shaft 29 and straddling dog 30, a spring casing 33 pivoted at 34 to dog 30, and a compression spring 35 bearing against the free end wall of casing 33 and against a shouldered pin 36 which is surrounded by the spring, which pin is provided with a transversely elongated cavity 37 in its head that is formed as a segment of a cylinder and fits against a similarly formed head on a pin 38 set into the rear part of gripper finger 32. The construction described minimizes wear on the spring and spring rod inasmuch as a flat seat at each end of the spring is maintained at all times. Casing 33 bears against a raised portion along one edge of bar 13, forming in effect a rail 39, and finger 32 bears against one of a series of gripper pads 40 that are elevated above the main portion of a contact bar 40'.

Dog 30 is provided with a lug 41 for raising finger 32 when shaft 29 is turned anti-clockwise, as viewed in Fig. 5; in other words, when it is turned away from sheet gripping position. The arrangement of parts is such that spring 35 acts through a shorter leverage arm the further the finger 32 is lifted off pad 40. This characteristic of the construction is illustrated more particularly in Figs. 8 and 9 where the parts are shown in gripper closing and opening positions, respectively, the leverage through which the spring acts in Fig. 8 being represented by the length of line 42, while the leverage through which the spring acts in Fig. 9 is represented by 40 the shorter line 43. Of course, the spring is more compressed when in the Fig. 9 position and therefore exerts greater force upon the pin 38 of the gripper finger than when the spring is in the less compressed condition shown in Fig. 8, but the increase in force is compensated for at least in part by the difference in leverage. The character of the springs and the proportions of the parts may be so chosen that the force which must be applied to turn shaft 29 either increases or decreases with increase in the distance of the fingers from their pads. Preferably the design is such that the required force is approximately uniform for all operating positions of the shaft.

Near one end of the bar 13 a collar 45 is secured to shaft 29 by means of a key 46. An arm 47 integral with collar 45 projects through an opening 48 in the bar and carries at its free end a roller 49 that is adapted to bear against a cam surface 50 at the free end of an arm 51 in a drum 52 over which the conveyor runs, see Fig. 2. These arms 51 in the drums at the two ends of the conveyor are actuated by suitable means, disclosed in my copending application referred to above, to swing arm 47 and shaft 29 for opening and closing the grippers at the proper times.

Collar 45 may have a spring casing 33 pivoted thereto which casing may be identical with those that are pivoted to dogs 30 and tending in like manner to turn the shaft 29 clockwise, as viewed in Fig. 6. The movement of the shaft in this direction, however, is limited by a stop finger 52' integral with collar 45 which is provided with an adjusting screw 53 that bears against a depressed surface 54 of contact bar 40'. This screw

53 and the dogs 30 are adjusted to permit the shaft 29 to turn slightly farther than is required to allow the grippers to close, so that there is a slight clearance between each of the lugs 41 and its associated finger 32. The stop finger 52' and screw 53 are located near one end of the shaft 29 to one side of the position occupied by a sheet so as not to interfere with the latter.

10 In the operation of the mechanism described, as each gripper bar approaches a drum at one end of the conveyor, it is locked in accurate register to the drum by means fully described in my aforesaid copending application, and while so locked, it transfers its sheet to the grippers of another sheet handling means, as for example to the impression cylinder of a printing press. The invention is also adapted, however, to use upon endless conveyors which retain their grip upon a sheet while it passes through a plurality of 20 printing units or other mechanisms for operating upon the sheet. It is evident that the gripper mechanism described herein, instead of being only temporarily locked in the drum 52, may, if desired, be constructed as a permanent part of such drum or of any other sheet handling cylinder, for example the impression cylinder of a printing or other machine, in which case, of course, the chains 10 and associated mounting devices for bar 13 would be omitted.

25 The gripper mechanism of this invention is particularly adapted for use in endless conveyors because the spring means is self-contained in the various units as distinguished from spring means conventionally employed at one end of a gripper bar for rocking a gripper shaft to sheet gripping position, such means generally employing springs of considerable length. In the present instance the springs 35 have the double function of pressing the various fingers 32 against the sheet with substantially uniform pressure, and of furnishing the principal force for rotating the shaft in the closing direction. It will be noted that the force of the spring 35 associated with each finger is applied to the finger itself which, being loose on the shaft, applies the force to the dog 30 and through the latter to the shaft. When the finger 32 meets its pad or grips a sheet therein the force of the spring is applied by the finger against the pad 40 instead of the dog 30. Thus when all the fingers are in sheet gripping position, all the dogs are free from the fingers and the shaft 29 is substantially entirely relieved of torsional stress due to springs 35. Under such conditions the shaft might be allowed to be free of any force biasing it in either direction. In the present construction, however, the spring 35 associated with collar 45 and stop finger 52' acts upon the shaft to hold the latter in its farthest clockwise position, as viewed in Fig. 6, that is, with screw 53 against bar 40', the purpose being to cause roller 49 to properly engage cam surface 50. The arrangement herein described is in contrast to the usual construction in which the spring for each gripper lies directly between each dog and its associated finger, and one or more large heavy springs are employed to hold the fingers in gripping position against the total effect of the individual springs for each gripper, thus placing a heavy torsional strain upon the shaft during the time a sheet is being gripped, and rendering difficult the proper setting of the grippers.

30 Having thus described my invention, I claim:

1. In mechanism of the character described, a shaft, a shaft support, a plurality of dogs secured

to the shaft, a corresponding number of gripper fingers loose upon the shaft in association with said dogs and adapted to be turned in one direction by the dogs, a spring for each finger, one end of which presses the finger toward sheet gripping position, and a mounting for each of said springs pivotally connected with said shaft and comprising an abutment for the opposite end of the spring, said spring tending to move said mounting about its pivot, said abutment contacting said shaft support for resisting movement of said mounting.

2. In mechanism of the character described, a shaft, a rail parallel to the shaft and movable bodily therewith, a plurality of fingers on the shaft, an operative connection between the shaft and each of said fingers, a spring for each finger one end of which presses the finger toward sheet gripping position, and a mounting for the spring pivotally connected with said shaft and comprising an abutment for the opposite end of the spring, said spring tending to move said mounting about its pivot, said abutment contacting said rail for resisting movement of said mounting.

3. In mechanism of the character described, a shaft, a rail parallel thereto and movable bodily therewith, a gripper finger adjustable along the shaft, an operative connection between the shaft and the finger, means for rocking the shaft to swing the finger away from sheet gripping position, a spring one end of which presses said finger toward sheet gripping position, and a mounting for the spring pivotally connected with said shaft and comprising an abutment for the opposite end of the spring, said spring tending to move said mounting about its pivot, said abutment contacting said rail for resisting movement of said mounting.

4. In mechanism of the character described, a shaft, a rail parallel thereto and movable bodily therewith, a gripper finger on the shaft, an operative connection between the shaft and the finger, means for rocking the shaft to swing the finger away from sheet gripping position, a spring the inner end of which presses said finger toward sheet gripping position, a spring casing comprising an abutment for the outer end of the spring, and a connection between the casing and the shaft comprising a pivot parallel to the shaft, the outer end of said casing contacting said rail.

5. In mechanism of the class described, a shaft, a rail parallel thereto and movable bodily therewith, a dog on the shaft held against rotation relative thereto, a gripper finger loose upon the shaft, means upon the dog for contacting the finger to swing the latter away from sheet gripping position when the shaft is rocked in one direction, a spring the inner end of which presses said finger toward sheet gripping position, a spring casing comprising an abutment for the outer end of the spring, and a pivotal connection parallel to said shaft for attaching the casing to the dog, the outer end of said casing contacting said rail.

6. In mechanism of the character described, a shaft, a rail parallel to the shaft and movable bodily therewith, a series of dogs on said shaft, means for securing the dogs in adjustable position both longitudinally and circumferentially of the shaft, a series of gripper fingers loose on the shaft each associated with one of said dogs and adapted to be turned in the finger retracting direction by its dog, a spring unit for each finger pivotally connected with its dog and having bearing at its opposite end against said rail, whereby

the force exerted by the unit varies with the angular relation between the unit and said rail, said spring units exerting force upon the fingers in the gripper closing direction.

5 7. In mechanism of the character described, a shaft, a rail parallel to the shaft and movable bodily therewith, a series of dogs secured on said shaft, a series of gripper fingers loose on the shaft each associated with one of said dogs and adapted to be turned in the finger opening direction by its dog, a pad for each finger against which the latter is adapted to close for gripping a sheet, a spring casing for each finger mounted at one end on a pivot parallel to said shaft carried by said dog and having bearing at its opposite end against said rail, a spring carried by each of said casings exerting force upon its finger in the closing direction, whereby the force exerted by the spring varies with the angular relation 10 between the spring support and said rail, a lever secured to said shaft, cam means adapted to cooperate with said lever to turn said shaft, said springs constituting the principal means exerting force in opposition to said cam means when the latter acts to move the fingers in the opening direction.

15 8. In mechanism of the character described, a shaft, a plurality of dogs secured to the shaft, a corresponding number of gripper fingers loose upon the shaft in association with said dogs and adapted to be turned in one direction by the dogs, a gripper pad for each finger, a body rigid with said pads, and individual spring means for each finger pivotally connected with said shaft, said 20 spring means having engagement with said body and said finger for biasing the finger in the other direction.

25 9. In mechanism of the class described, a gripper pad, a rail, an oscillatable shaft parallel thereto, a gripper finger oscillatable about and adjustable along said shaft, spring means having an end bearing upon and adjustably slidable lengthwise of said rail, said spring means being adapted to rock said finger on said shaft into contact with said pad, and a dog on said shaft normally out of engagement with said finger adapted when the shaft is turned in one direction to engage and move said finger away from said pad in opposition to the force of said spring means, said dog and said spring means being interconnected by a pivot extending parallel to said shaft.

30 10. In mechanism of the character described, an elongated support, a gripper pad at one side of said support, a rail at the opposite side of said support, a shaft oscillatably mounted on said support between said pad and rail, a gripper finger oscillatable upon said shaft, spring means comprising a casing bearing at its outer end against said rail, said casing having a pivotal connection with said shaft and carrying a spring pressed plunger having pivotal connection with said gripper finger, said pivotal connections being parallel to said shaft and spaced apart, the expansion of the plunger spring tending to rock the shaft in one direction and close said finger against said pad, and the rotational movement of the shaft in the opposite direction tending to compress the plunger spring and separate the finger from the pad.

35 11. In mechanism of the character described, a shaft, bearings therefor, a support fixed with respect to said bearings, a plurality of dogs secured to said shaft, a corresponding number of gripper fingers loose upon the shaft in association with said dogs, spring means operatively

connected with each finger and the corresponding dog and reacting directly against said support, said spring means functioning individually to urge said fingers towards closed position and collectively to oppose motion of said shaft and dogs toward finger opening position.

12. In mechanism of the character described, a shaft, a plurality of dogs secured to said shaft, a corresponding number of gripper fingers loose upon the shaft in association with said dogs and adapted to be turned in one direction by the dogs, a gripper pad for each finger, a longitudinally deformable coil spring for each finger adapted to

5 press the finger against its pad, a pivotal connection between each said spring and its finger for transmitting the force of the spring to the finger, a support for the opposite end of said spring, said support being fixed with respect to said pads, said pivotal connection being offset from a line joining said shaft and said support, and the deformation of said spring in response to the finger opening movement of said dog being compensated by the movement of said pivoted connection toward said line.

CHRISTEN R. KADDELAND.
